UNITED STATES PATENT OFFICE.

FREDERICK S. CHASE, OF WATERBURY, CONNECTICUT.

DESIGN FOR A POCKET OIL-CAN.

SPECIFICATION forming part of Design No. 26,871, dated April 6, 1897.

Application filed February 1, 1897. Serial No. 621,570. Term of patent 7 years.

To all whom it may concern:

Be it known that I, FREDERICK S. CHASE, of Waterbury, in the county of New Haven and State of Connecticut, have invented a new 5 Design for a Pocket Oil-Can; and I do hereby declare the following, when taken in connection with the accompanying drawings and the letters of reference marked thereon, to be a full, clear, and exact description of the same, 10 and which said drawings constitute part of this specification, and represent, in—

Figure 1, a view in side elevation of an oil-can containing my design; Fig. 2, a view thereof in side elevation; Fig. 3, a view in cross-section on the line *a b* of Fig. 1.

This invention relates to a new and original design for an oil-can of the pocket type; and it consists in the shape or configuration hereinafter shown and described.

20 My newly-designed oil-can has a cross-sectionally-oval body *A*, having a flat bottom *A'*

and convex shoulders *A²* *A²*, merging into a short corrugated circular neck *A³*, which is overhung by the flange *B* of the spout *B'* (shown by broken lines) and inclosed by a cylindrical cap *C*. Both faces of the body *A* of the oil-can are struck up to form oval panels *D*, surrounded by concentric beads *d d*. The major axes of these oval panels are arranged parallel with the longitudinal axes of the body 30 of the oil-can.

I claim—

The design for a pocket oil-can as herein shown and described.

In testimony whereof I have signed this 35 specification in the presence of two subscribing witnesses.

FREDERICK S. CHASE.
